Attorney

UNITED STATES PATENT OFFICE.

JOHN A. SANNER, OF PAGE, WEST VIRGINIA.

RAIL JOINT.

Application filed June 16, 1923. Serial No. 645,759.

To all whom it may concern:

Be it known that I, JOHN A. SANNER, a citizen of the United States, residing at Page, in the county of Fayette and State of West Virginia, have invented certain new and useful Improvements in Rail Joints, of which the following is a specification, reference being had to the accompanying drawings.

10 This invention relates to railroad constructions, particularly to means for holding together the meeting ends of the rails of temporary tracks laid in mines and other places, and has for its object the provision 15 of a securing device including wedge means for positively locking the parts together and preventing any casual separation.

Another feature of the invention is the provision of a joint and securing means of 20 such character that the use of bolts or other equivalent elements requiring special tools for their placement will be eliminated, the advantage being that the temporary track may be laid or taken up quickly and easily.

25 Another feature is the provision of securing means at the joint which will operate to reinforce the structure and prevent disaligning of the rails in any direction.

An additional object is to provide a structure of this character which will be simple 30 and inexpensive, highly efficient in use, durable in service and a general improvement in the art.

With the above and other objects and advantages in view, the invention consists in 35 the details of construction to be hereinafter more particularly described and claimed, and illustrated in the accompanying drawings, in which:

40 Figure 1 is an elevation showing one side of a pair of meeting rails equipped with my joint structure and securing means;

Figure 2 is an elevation of the opposite side;

45 Figure 3 is a horizontal section on the line 3—3 of Figure 2;

Figure 4 is a cross sectional view through one of the securing members, the view being taken on the line 4—4 of Figure 2.

50 Figure 5 is a fragmentary perspective view showing one end of the elongated bar which receives the wedge.

Referring more particularly to the drawings, the numeral 10 designates rails arranged in end to end relation as shown. Disposed against opposite sides of the rails and

bearing upon the webs and bases thereof are angle plates 11 formed with holes 12 which register with similar holes 13 in the rails. These holes are circular in shape and are the 60 same as are ordinarily provided for the passage of securing bolts which are employed in the ordinary construction.

Disposed against the outer side of one angle plate is an elongated bar 14 formed 65 with key hole slots 15 which include circular portions 16 and square portions 17. The bar 14 is movable transversely with respect to the angle plate against which it is disposed so that either the circular portions 16 or the 70 square portions 17 of the key hole slots may be brought into registration with the circular holes 12 and 13. The inner face of the bar 14 is grooved or channeled as indicated at 18 to define a longitudinally extending lip 19 for a purpose to be described.

Instead of using the ordinary bolts commonly employed in rail joint constructions, I provide fastening members 20 each of which includes an elongated cylindrical shank 21 80 adapted to be fitted within the holes 12 and 13 and terminating at one end in a head 22. The other end of each fastening member is reduced and squared as shown at 23 so as to be received within the squared portion 17 85 of a key hole slot, and this squared portion terminates in a tapered head 24 of a diameter sufficiently small to pass through the circular portion 16 of a key hole slot.

For effecting a locking action I provide 90 an elongated wedge 25 which fits within the groove or channel 18 with one edge bearing upon the lip 19 and its other edge bearing against the under sides of the squared reduced portions 23 of the fastening members. 95 It should be stated that the groove or channel 18 is wedge shaped or tapered from end to end for cooperative relation to and engagement with the wedge.

In assembling the joint, the angle plates 100 11 are placed against the opposite sides of the rails and the fastening members 20 are passed through the holes 12 and 13. The bar 14 is then placed against the angle plate beyond which the fastening members 20 extend and is so positioned that the circular portions 16 of the key hole slots will engage over the heads 24 of the fastening members. The bar 14 is then permitted to move downwardly, or is forced downwardly if necessary, so that the squared portions 17 of the slots will engage upon the squared ends 105 23

- of the fastening members. The wedge 25 is then inserted within the groove or channel 18 and is driven in so as to move the bar 14 outwardly with respect to the adjacent angle 5 plate and consequently exert an outward pressure on the heads 24 which will hold all the parts absolutely rigid. It is preferable that the large end of the wedge be formed with an impact receiving head 26 and that 10 its smaller end be provided with a plurality of holes 27 within any one of which may be engaged a cotter or other pin 28 to engage against the end of the bar 14 and prevent accidental retraction of the wedge.
- 15 To take up the track, the cotter pin is removed and the wedge 25 is withdrawn, after which the bar 14 is lifted to bring the circular portions 16 of the key hole slots opposite the heads 24, whereupon the bar 20 may be readily removed so that the fastening members and angle plates may likewise be removed and the rails disconnected.

From the foregoing description and a study of the drawing it will be apparent that 25 I have thus provided a simply constructed, inexpensive and highly efficient rail joint and securing means which may be put together or taken apart without the use of any special tools and without employing bolts 30 or other similar fastening members. Owing to the provision of the wedge means the locking action can be made positive so that any displacement of the parts under strain will be absolutely prevented.

35 While I have shown a preferred form of the invention it is, of course, to be understood that I reserve the right to make such changes in the form, construction and arrangement of the parts as will not depart 40 from the spirit of the invention or the scope of the subjoined claims.

I claim:—

1. Securing means for the meeting ends of rails, comprising angle plates disposed 45 against opposite sides of the rails at the meeting ends thereof, the rails and angle plates being formed with registering holes, a bar disposed against the outer side of one angle plate and formed with key hole slots 50 registering with said holes, fastening members extending through said holes and hav-

ing reduced angular ends for engagement within the smaller ends of the key hole slots, and wedge means between said bar and the adjacent angle plate for forcing the former 55 outwardly with respect to the latter, the inner side of said bar being formed with a tapered channel receiving the wedge and defining a lip engaged by one edge thereof, the other edge of the wedge engaging the under 60 sides of said fastening members.

2. Means for securing the meeting ends of rails comprising angle plates disposed against opposite sides of the rails and 65 formed with registering circular holes, headed fastening members passing through said holes and having reduced angular extensions terminating in tapered heads of a diameter to pass through said holes, a bar disposed against the outer face of one angle plate and 70 formed with key hole slots engageable over said tapered heads with their smaller ends engaging upon the angular extensions of the securing members, said bar being movable vertically with respect to the rails, and 75 means for applying outward pressure on the bar.

3. Means for securing the meeting ends of rails comprising angle plates disposed 80 against opposite sides of the rails and formed with registering circular holes, headed fastening members passing through said holes and having reduced angular extensions terminating in tapered heads of a diameter to pass through said holes, a bar 85 disposed against the outer face of one angle plate and formed with key hole slots engageable over said tapered heads with their smaller ends engaging upon the angular extensions of the securing members, said bar 90 being movable vertically with respect to the rails, and means for applying outward pressure on the bar, comprising a wedge, the inner side of the bar being channeled to receive the wedge and having a lip engaged 95 thereby, the other edge of the wedge bearing against the angular extensions of the fastening means.

In testimony whereof I hereunto affix my signature.

JOHN A. SANNER.
